UNITED STATES PATENT OFFICE.

DAVID ALTMAN, OF MACON, GEORGIA.

CAR-COUPING.

SPECIFICATION forming part of Letters Patent No. 450,904, dated April 21, 1891.

Application filed September 8, 1890. Serial No. 364,359. (No model.)

To all whom it may concern:

Be it known that I, DAVID ALTMAN, of Ma-
con, in the county of Bibb, State of Georgia,
have invented a new and useful Improvement
5 in Car-Couplings, of which the following is a
specification.

My invention is an improvement in car-
couplings; and it consists in certain novel
constructions and combination of parts, as
10 will be hereinafter described, and pointed out
in the claims.

In the drawings, Figure 1 is a perspective
view of a car-coupling embodying my invention.
15 Fig. 2 is a vertical longitudinal section
of the coupling. Fig. 3 is a cross-section of
the coupling. Fig. 4 shows a modification of
the means for preventing the pin from jolting
upward, and Figs. 5 and 6 show intermediate
20 devices between the lever and the side
of the car.

The draw-head A may be secured to the
car-frame in any suitable manner, and has its
front end formed square to provide a proper
abutment for the meeting draw-head, and
25 such end is mortised to receive the link, the
mouth of such mortise being rounded or con-
caved on all sides to properly guide the link
into the draw-head. This draw-head is
adapted by such flaring of the mouth to re-
30 ceive the ordinary link, whether such link be
straight or bent in the ordinary manner, and
to couple with higher or lower cars. The
draw-head is secured to the car-frame and is
provided with the pin-opening B, formed
35 through its top and adapted to permit the pin
to swing back enabling the automatic cou-
pling of the cars, as will be readily understood,
it will be seen that no matter whether the pin
hangs vertically or slightly to one side, the
40 entering link will push the coupling-pin back
and effect the automatic coupling, as desired.
The draw-head may have its top flat, as shown,
or suitably rounded and is provided near its
side edges on opposite sides of the pin-open-
45 ing with guide-frames C, which may be formed
integral with the draw-head or be made sepa-
rately and suitably secured to the said draw-
head, as desired. These frames serve to retain
the levers D, presently described, the said le-
50 vers fulcruming at the base of said frames, as
shown. These levers are constructed at their
inner ends to interlock, so that the depre-

sion of the outer end of either of the said le-
vers will effect the elevation of the inner end
of both, such levers being suitably engaged 55
with the pin to lift such pin to uncoupled po-
sition when the levers are properly operated.

In the construction shown the levers are
bifurcated at their inner ends, providing the
slots D', which receive the pin and the arms 60
or portions d'd', the portions d of each lever
being arranged to lap upon the portion d' of
the other lever, so that when either lever is
depressed at its outer end its portion d' at its
inner end will serve to lift the inner end of 65
the other lever, so that the pin can be readily
adjusted to uncoupled position from either
side. It will be noticed that the levers widen
out at D² just inside the guide and retaining
frame C, so that the levers are held by the 70
shoulders or widened parts D² from moving
outward through the frame C and thus be-
coming displaced. These levers may be up-
turned at their outer ends, as shown, to render
the operation of uncoupling easier. To hold 75
the pin in uncoupled position I provide chains
E, secured to the draw-head and provided
with rings F, movable along the levers and
into and out of notches f. When either of
80 the rings is in its notch f, it will secure its le-
ver in such position as to hold the pin ele-
vated or uncoupled.

To prevent the pin from jolting or jarring
upward, I provide each lever with a clip or
clamp G, secured at one end to the lever and 85
arranged at its opposite end to bear upon the
coupling-pin and hold it from upward move-
ment independent of the levers. In the con-
struction as shown the clip or clamp is bifur-
cated, forming arms which bear on opposite 90
sides of the pin. These clips or clamps serve
as stops to prevent the independent upward
movement of the pin and are preferred; but
it will be understood that such stop construc-
95 tion might be effected by the construction
shown in Fig. 4 by providing the coupling-pin
below the levers with a pin h or shoulder H, or
both.

While the levers may be operated directly,
it may be preferred to employ in connection 100
with them pull or push rods I or J, as shown
in Figs. 5 and 6, in which case the outer ends
of the levers have downwardly or upwardly
projected arms, which are connected with

longitudinally-sliding arms, which latter extend to the sides of the car and have catch portions K to hold the levers in uncoupled positions.

5 It will be understood that the coupling herein described is an improvement upon my former car-coupling covered by me in application for patent filed May 31, 1890, Serial No. 356,898, patented September 2, 1890, No. 435,787.

The construction as described is simple, convenient, easy of operation, and enables the cars to be coupled and uncoupled without requiring the operator to go between the cars.

15 Having thus described my invention, what I claim, and desire to secure by Letters Patent, is—

1. In a car-coupling, the combination, with the draw-head, of the coupling-pin and the 20 pin-operating levers arranged to interlock at their inner ends, substantially as set forth.

2. The improved car-coupling herein described, comprising the draw-head, the coupling-pin, the pin-operating levers having their 25 inner ends bifurcated, forming arms $d d'$, the arms d of each lever being arranged to lap upon the arm d' of the other lever, all substantially as set forth.

3. In a car-coupling, the combination of the 30 draw-head, the coupling-pin, the frame C, and the levers D, passed through said frames and engaged at their inner ends with the pin, the said levers being provided with shoulders D^2 , whereby they are prevented from movement 35 outwardly through frame C, substantially as set forth.

4. In a car-coupling, the combination, with the draw-head, of the coupling-pin, the frame C, the levers D, having slots D' , arms $d d'$, and shoulders D^2 , all arranged and adapted for 40 use substantially as set forth.

5. In the herein-described car-coupling, the combination, with the draw-head, of the coupling-pin, the pin-operating levers, and the chains E, having rings F, arranged to slide 45 on said levers, all substantially as set forth.

6. The combination, with the car-coupling, of the draw-head having frames C, the coupling-pin, the levers D, having slots D' , arms $d d'$, and shoulders D^2 , the chains E, and the 50 rings F, all substantially as set forth.

7. In a car-coupling, the combination of the draw-head, the coupling-pin, the pin-operating levers, and a stop construction whereby to prevent the upward movement of said pin 55 independent of the levers, all substantially as set forth.

8. In a car-coupling, the combination, with the draw-head, of the coupling-pin, the levers for operating the same, and the clamps or 60 clips secured to said levers and bearing upon the pin, substantially as set forth.

9. In a car-coupling, the combination of the draw-head, the coupling-pin, the levers D, and the longitudinally-sliding rods connected 65 with the said levers, all substantially as set forth.

DAVID ALTMAN.
